MEANS AND METHOD FOR MAKING NUTS

Richard Lester Wilcox, Waterbury, Conn., assignor to The Waterbury Farrel Foundry and Machine Company, Waterbury, Conn., a corporation of Connecticut

Application January 8, 1932, Serial No. 585,526

22 Claims. (CL 10—86)

This invention relates to new and improved means and method for making nuts, more particularly of the castellated type.

It is the object of this invention, among other things, to make a nut of the type indicated from a blank by pressure and to provide mechanism therefor whereby the nut will be produced in its substantially finished form with only a very minimum amount of labor to be performed thereon to make it a complete nut.

The type of nut illustrated in the drawings is of the castellated type with a plurality of castles or lugs upon one face thereof, which are substantially parallel with and in extension of some of the straight sides of the nut with an opening through the nut which may be counter-bored at one end or at opposite ends if desired, the inner walls of the castles or lugs being substantially smooth, without threads, and located at a point sufficiently distant from the axis of the nut so as to be out of the path of the tool during the threading operation. Either or both of the inner and/or outer walls of the castles or lugs may be beveled without operations other than necessary to form the nut.

To these and other ends my invention consists in the means and method for making nuts as is hereinafter described and more particularly pointed out in the drawings.

Referring to the drawings, in which like numerals of reference indicate like parts in the several figures;

Figure 1 is a perspective view of a complete nut made under this invention;

Figure 2 an end view and elevation respectively of the blank as it is cut from the rod length or otherwise produced;

Figure 3 an end view and elevation of the blank after its first pressure operation if such operation seems advisable;

Figure 4 an end view and elevation of the blank after a subsequent pressure operation;

Figure 5 an end view and elevation thereof after a subsequent operation;

Figure 6 an end view and elevation of a nut as completed by the means and method herein disclosed and after being threaded;

Figure 7 a sectional view of the mechanism used to produce the nut illustrated with a rod length at the first station, and a blank in its partially completed form in each of the other stations, the nut shown in section at station 4 having a collar that is substantially the same diameter as the distance across the face of the nut between the flat sides;

Figure 8 a fragmentary sectional view of a portion of the tools at the last pressure station;

Figure 9 a face view of the punch shown in Figure 8;

Figure 10 a portion thereof, the part in section being taken generally upon line 10—10 of Figure 9;

Figure 11 is a perspective view of that portion thereof adjacent to its working face;

Figure 12 is a perspective view of the punch 10 at the third station;

Figure 13 an end view thereof; and

Figure 14 a fragmentary sectional view taken generally upon line 14—14 of Figure 13.

The mechanism herein shown may be associated with any pressure machine, such as a press or the like, although not limited thereto.

As shown herein, 15 indicates the machine bed or the like with which a die block 16 is connected, the latter having associated therewith a plurality 20 of dies or the like at different stations.

The die 17 at station 1 being a cut-off die; dies 18 and 19 at stations 2 and 3 respectively being pressure dies, as is also die 20 at station 4, and the die 21 at station 5 being a piercing die. 25

The cut-off die 17 has an opening therethrough of substantially the same shape and size in cross section as the wire rod 22, from which the blanks 23 are cut by a knife 24.

In the face of the pressure die 18 is an opening 30 of substantially the same diameter as the blank 23 and if desired the bottom corners at 25 may be flared or rounded slightly which form an angular face 26 on the blank 23.

The purpose of the operations at this station is to assure the end faces of the blank being square with the sides, and parallel with each other; if the nature of the metal in the blank is such that it does not cut off substantially square with the knife 24, and the flared or rounded corners 25 in the die 18 insure greater wear of the die and a longer life thereof. 35

The operations at station 2 are not absolutely essential in this invention, but with some types of nut and material are desirable. 40

Movable in an opening in the pressure die 18 is a rod 52, the face of which in one of its positions is substantially flush with the bottom of the recess in the die and is actuated by well known mechanism to eject the blank from said recess in timed relation with other parts. 45

Die 19 is similarly provided with a recess in its upper face and a knockout rod 27 actuated by a plunger 28 or the like, which rejects the 50

55

blank from the recess in timed relation with other parts.

The die 20 has an opening therein of substantially the same shape in cross section as the finished nut, which, as illustrated herein, is hexagonal.

Within the bore of the die 20 is an abutment block 29 having an opening therein of substantially the same diameter as the collar 30 on the 10 nut 31 and within which is the knockout rod 32.

The piercing die 21 is held within a die holder 33 and thereabove and in spaced relation therewith is a stripper plate 34.

A plunger, gate or punch holder 35 is actuated 15 in any well known manner toward and away from the die block 16 and mounted therein are a plurality of punches severally designated 36, 37, 38 and 39.

Associated and movable with the plunger or gate 35 is a backing plate 56, against which contacts the ends of the several punches.

The end of the punch 36 is substantially the same diameter as that of the blank 23. After the blank is cut from the rod 22 and transferred in 25 any convenient or well known manner to a position where it is in line with the recess in the die 18, it is projected into the recess by the punch 36 and both ends are squared so as to be substantially parallel with each other and at right angles 30 to the length of the blank. This operation insures a blank that is square and flat at both ends and without a bur, fin or the like thereon for presentation at its next succeeding station. This operation 35 may be omitted within the scope of the invention.

The punch 37 is provided with an opening or bore 53 therein and a recess 54 with angular or flaring walls in its operating face, as is the recess in the die 19 to form the flaring angular walls 40 upon the opposite faces of the blank.

Extending into the body of the punch from the bottom of the recess 54 are a plurality of recesses 41 corresponding in number and shape with the number and shape of castles or lugs 42 upon the 45 nut and into which the metal may flow. These notches are of greater depth than the height of the castles or lugs 42 so that the flow of the metal therein is not limited to a direction substantially parallel with the axis of the punch.

50 The shape and relative position of the side walls 55 of these notches are determined in part by the shape and position of the side walls of the castles or lugs 42.

Within the spirit of this invention and the scope 55 of the appended claims, the shape of the castles or lugs may be varied from that illustrated in the drawings.

Within the punch 37 is a combined pressure and knockout rod 43 which moves within the open- 60 in or bore 53 and is substantially the same diameter as the flat surfaces of the blank between the inner edges of the castles or lugs, as shown in Figure 4. This rod 43 at its inner end contacts with the backing plate 56, at which time its outer 65 end is in upsetting pressure position and is actuated to eject the blank from the punch by the coil spring 44.

The knockout rod 27 insures the ejection of the blank from the recess in the die 19 and likewise 70 the knockout rod 32 from the recess in the die 20.

The blank is compressed at station 3 between the bottom of the recess in the die 19 and the end of the rod 27 on one side and the bottom of the recess in the punch 37 and the end of the rod 43 75 on the other side, the displaced metal flowing

into the notches 41 to produce the blank substantially as shown in Figure 4. The flow of this displaced metal is unrestrained axially because the notches 41 are deeper than the possible flow thereof, but is held against lateral flow by the side walls 55 of such notches.

The blank as shaped at station 3 is presented at station 4 in the recess in the die 20 and against the projection 46 on the end of the knockout rod 32 by the punch 38. This punch corresponds in shape in cross section with that of the finished nut and has a projection 45 upon its operating face similar to a like projection 46 upon the knockout rod 32 whereby depressions 47 are formed in the end faces of the nut, each of which becomes the counter-bore at the end of the opening 57 in the nut made by a subsequent piercing operation. During the movement of the punch 38 the projection 45 thereon first contacts with the substantially flat face 58 of the blank and applies pressure thereto.

In each of three of the flat sides of the punch 38 adjacent to the end thereof, is a recess 48. These are of substantially the same width as the castles or lugs 49 on the finished nut, but of greater depth, so that as pressure is applied to the opposite faces of the blank, the metal may flow into the recesses unrestrained substantially parallel with the axis of the punch and die, but confined against lateral flow by the side walls of the recesses whereby the width of the castles or lugs is determined.

The cross sectional shape of the recesses 41 and 48 are substantially the same so that the width of the castles or lugs as first formed at station 3 is continued at station 4.

The nut has now acquired its complete exterior shape and is presented to station 5 where the punch 39 pierces the hole 51 therethrough. The slug 50 cut by this punch drops through the opening 51 into a receptacle conveniently arranged to receive it, being the only waste piece of metal resulting from the operations described.

By the method and mechanism described there is formed from a blank and entirely by pressure 45 a castellated nut, wherein the castles or lugs are substantially parallel with and in extension of some of the sides of the nut, the inner walls located a sufficient distance from the axis of the nut to be outside of the line of the threads in the 50 opening in the nut and if desired some of the walls of the castles or lugs being curved or angular.

What I claim as new and desire to secure by Letters Patent is:

1. The method of forming nuts of the castellated type, which includes first shaping a substantially cylindrical cold blank so that one face thereof is domed shape at spaced intervals and embryo castles project axially outwardly in the spaces 60 therebetween and thereafter by separate tools applying pressure to said domed surfaces while in a confining area of predetermined configuration, whereby said domed surfaces will be flattened and the pressure applied thereto will cause the metal 65 in the blank to flow outwardly to form the finished exterior of the nut and the embryo castles to be extended in height.

2. In combination with a die; a punch having an opening therethrough; a plurality of axial recesses 70 extending radially from said opening and pressure faces between said opening and recesses at an angle to the axis of the punch, thereby to shape by pressure a substantially cylindrical cold blank 75 so that one end thereof will have a plurality of 75

spaced angular faces thereon, and a similar number of axial projections; a second die having an opening of substantially the same shape in cross section as that of the body of the finished article; a punch having a plurality of pressure faces; and means for subjecting a blank within the die opening to the pressure of the punch axially of the blank and upon the aforementioned spaced angular faces, whereby the metal in the blank is caused 10 to flow outwardly to the side walls defining the die opening, thereby to change the angular faces so that they will be at substantially a right angle to the axis of the blank and the axial projections may be increased in height by reason thereof to 15 form castles or lugs on the face of the blank.

3. The method of forming nuts of the castellated type which includes first applying pressure to an end face of a substantially cylindrically cold blank at spaced intervals about the edge thereof, and 20 continuing such pressure to form a plurality of spaced areas upon said face that are inclined downwardly toward the outer edge thereof and the spaces between said areas are projected upwardly to form embryo castles, and thereafter, 25 while in a confining area, applying pressure to that portion of the face of the blank that is centrally located between the embryo castles and to said spaced areas to cause the inclined faces of the 30 spaced areas to be flattened to a plane at substantially a right angle to the axis of the nut and increase the embryo castles in relative height while the blank remains in its initial cold state.

4. The method of forming nuts of the castellated type which includes first applying pressure to an 35 end face of a substantially cylindrical blank at spaced intervals about the edge thereof, and continuing such pressure to form a plurality of spaced areas upon said faces that are inclined downwardly toward the outer edge thereof and the spaces between said areas are projected upwardly to form embryo castles, and thereafter, while in a 40 confining area, applying pressure to that portion of the face of the blank that is centrally located between the embryo castles and to said spaced areas to cause the inclined faces of the spaced 45 areas to be flattened to a plane at substantially a right angle to the axis of the nut and increase the embryo castles in relative height, the top and outer faces of the embryo castles being at substantially a right angle to each other but at an acute 50 angle to each of the adjoining surfaces.

5. The method of forming nuts of the castellated type which includes first applying pressure to an 55 end face of a substantially cylindrical blank at spaced intervals about the edge thereof, and continuing such pressure to form a plurality of spaced areas upon said face that are inclined downwardly toward the outer edge thereof and the spaces between said areas are projected upwardly to form embryo castles and thereafter, while in a 60 confining area, applying pressure to that portion of the face of the blank that is centrally located between the embryo castles and to said spaced areas to cause the inclined faces of the spaced areas to be flattened to a plane at substantially a right 65 angle to the axis of the nut and increase the embryo castles in relative height, and each having a top that flares inwardly and outwardly toward the said face of the nut.

70 6. The method of forming nuts of the castellated type, which includes first shaping a substantially cylindrical blank so that one face thereof is domed shape at spaced intervals and embryo castles project axially outwardly in the spaces

therebetween and thereafter by separate tools applying pressure first to that portion of said face that is centrally located between the said embryo castles and gradually to said spaced domed areas until said domed areas are substantially flat, the 5 last mentioned pressure being applied while the blank is in a confining area of predetermined configuration.

7. The method of forming nuts of the castellated type, which includes first shaping a substantially 10 cylindrical blank so that one face thereof is domed shape at spaced intervals and embryo castles project axially outwardly in the spaces therebetween and thereafter by separate tools applying pressure first to that portion of said face 15 that is centrally located between the said embryo castles and gradually to said spaced domed areas until said domed areas are substantially flat and the space centrally located between the castles 20 is depressed.

8. The method of forming nuts of the castellated type, which includes first shaping a substantially cylindrical blank so that one face thereof is domed shape at spaced intervals and embryo castles project axially outwardly in the spaces therebetween 25 and thereafter by separate tools applying pressure to said domed surfaces while in a confining area of predetermined configuration, whereby said domed surfaces will be flattened and the pressure applied thereto will cause the metal in the blank 30 to flow outwardly to form the finished exterior of the nut and the embryo castles to be extended in height and thereafter removing a portion of the blank between the castles to form a hole there- 35 through and threading the same.

9. The method of forming nuts of the castellated type, which includes first shaping a substantially cylindrical blank with one face domed and the opposite face dome shape at spaced intervals; and embryo castles projecting axially outward in the spaces therebetween, and thereafter by separate tools apply pressure to the first mentioned domed face and to that portion of the last mentioned face that is centrally located 40 between the embryo castles and gradually to said spaced domed areas until said domed areas are substantially flat, except where the castles 45 are located and the space between the castles having a depression therein.

10. Means for making nuts, comprising in part a punch having an axially extending bore, an annular substantially flat end face, a plurality of recesses extending radially from the bore and a pressure face between each of said recesses, 50 spaced from the said end face, that flare inwardly from said end face to said bore, in combination with a movable member within the opening, the end face of which during the pressure movement of the punch is spaced inwardly 55 from said end face and in substantially the same plane as the inwardly flaring pressure faces as they join the said opening.

11. Means for making nuts, comprising in part a punch having an axially extending bore, an annular substantially flat end face, a plurality of recesses extending radially from the bore and a pressure face between each of said recesses, 60 spaced from the said end face, that flare inwardly from said end face to said bore, in combination with a movable member within the opening, the end face of which during the pressure movement of the punch is spaced inwardly 65 from said end face and in substantially the same plane as the inwardly flaring pressure faces as 70 75

- they join the said opening, and means for actuating the movable member independently of the punch, after the pressure operation, whereby to eject a blank from the punch.
5. 12. Means for making nuts, comprising in part a punch having an axially extending bore and an annular substantially flat end face concentric with said bore, a plurality of pressure faces that flare inwardly from the inner edge of said end face, the juncture of said pressure faces with said bore defining a plane which is spaced axially from the plane of said end face and in the direction of the body portion of said punch, in combination with a movable member within the bore, the end face of which during the pressure movement of the punch lies substantially in said first mentioned plane.
13. The method of making castle nuts which comprises upsetting a section of stock and in 20 the same operation forming castle prongs at one end of the section, and then forming corners on the blank by squeezing some of the metal of the blank outwardly between each pair of castle prongs.
25. 14. The method of making a castellated nut blank comprising shaping a blank to provide a substantially dome-shaped surface on one face thereof and simultaneously initiating the formation of the locking lugs on the dome-shaped surface, then compressing all portions of the blank save for the locking lugs to shape the blank to its finished configuration while simultaneously extruding metal to complete the formation of the locking lugs.
35. 15. The method of making a castellated nut blank comprising shaping a blank and simultaneously initiating the formation of the locking lugs of the nut, compressing all portions of the blank save for the locking lugs while placing the blank in its finished configuration and simultaneously extruding metal to complete the locking lugs and off-setting the lugs outwardly.
16. Mechanism for the formation of castellated nut blanks, comprising a punch having a concaved area on its working face provided with recesses for forming locking lugs on a blank, said recesses opening at said face and extending radially for a distance substantially coextensive with the radius of said concaved area and extending longitudinally of the punch a length greater than the height of the said lugs.
17. The method of making a castellated nut blank, comprising initially shaping a blank and simultaneously initiating the formation of the locking lugs of the nut, then compressing all portions of the blank save for the locking lugs while placing the blank in its finished configuration, and simultaneously extruding metal to complete the locking lugs and allowing the extruded metal to flow unhindered.
18. The method of making a castellated nut blank comprising shaping a blank to provide a substantially dome-shaped surface on one face thereof and simultaneously initiating the formation of the locking lugs on the dome shaped surface, and compressing the blank save for the locking lugs while further shaping the blank and simultaneously extruding material from the blank to complete the formation of the locking lugs.
19. The method of making a castellated nut blank comprising shaping a blank to provide a substantially dome-shaped surface on one face thereof, initiating the formation of the locking lugs on the dome-shaped surface, and compressing the blank save for the locking lugs while further shaping the blank and extruding material from the blank to complete the formation of the locking lugs.
20. The method of making a castellated nut blank comprising shaping a blank and simultaneously initiating the formation of the locking lugs of the nut, compressing the blank save for the locking lugs while placing the blank in its finished configuration, and simultaneously extruding material from the blank to complete the locking lugs, and off-setting the lugs outwardly.
21. The method of making a castellated nut blank comprising shaping a blank and simultaneously initiating the formation of the locking lugs of the nut, then compressing the blank, save for the locking lugs while further shaping the blank, and simultaneously extruding material from the blank to complete the locking lugs and allowing the extruded material to flow unhindered.
22. The method of making a castellated nut blank comprising shaping a blank, initiating on the blank the formation of the locking lugs of the nut, compressing the blank save for the locking lugs while further shaping the blank, and extruding material from the blank to complete the locking lugs and allowing the extruded material to flow unhindered.

RICHARD LESTER WILCOX.
